UNITED STATES PATENT OFFICE.

INA PERMELIA JOHNSON, OF HOLLYWOOD, CALIFORNIA.

LINGERIE-STRAP HOLDER.

Application filed September 1, 1926. Serial No. 133,043.

This invention relates to improvements in wearing apparel retainers, and has particular reference to a lingerie strap holder.

The principal object of the invention is to provide a simply and economically constructed device adapted to be conveniently positioned to retain there-between a lingerie strap, and further being equipped with additional fastening means whereby the device may be adjustably secured to the shoulder portion of a blouse or like article of wearing apparel.

An additional object of the invention is to provide a novel lingerie strap holder that will securely hold the strap in position so that the danger of the same becoming displaced is eliminated.

Other objects and advantages will be apparent during the course of the following description.

In the accompanying drawings forming a part of this specification and in which like numerals are employed to designate like parts throughout the same,

25 Figure 1 is a side elevation of the holder as it would appear secured to an article of wearing apparel and positioned upon the shoulder of the wearer,

30 Figure 2 is a side elevation of the device per se,

Figure 3 is a top plan view of the same,

Figure 4 is a transverse vertical section through the keeper portion of the holder on the line 4-4 of Figure 2, and

35 Figure 5 is a fragmentary detail view showing the relative positions of the parts of the device, with a lingerie strap being shown in section and likewise a portion of the blouse of the wearer being shown in section.

40 It oftentimes happens that an unsightly appearance is occasioned due to the lingerie straps hanging loosely over the shoulders of the wearer, and that have a tendency to 45 slide over the arms. This untidy display is particularly noticeable where the dress or blouse is made of sheer material.

To overcome this annoyance and to likewise provide an economically and simply constructed article for retaining the lingerie straps, I have devised the present invention whereby a lingerie strap may be readily positioned between the parts of the holder and will be prevented from displacement therefrom and further embody in the device a fastening element, such as a pin, so that the

retaining device may be readily secured to the blouse or dress at the shoulder portion thereof.

In the accompanying drawings wherein 60 for the purpose of illustration is shown a preferred embodiment of my invention, the numeral 6 indicates a metal strip or bar preferably made of flexible material which terminates at one end in a downwardly-bent 65 portion 7 serving as a keeper for a lower metal strip or bar 8 normally positioned in alignment with the strip 6 and spaced therefrom.

The strip 8 is pivotally secured as at 9 to 70 the strip 6 so that the strip 8 may be actuated to assume the position shown to advantage in Figure 3, whereby a lingerie strap as indicated at 10 may be readily positioned between the strips 6 and 8 and then 75 retained there-between by virtue of the notch 11 provided in the strip 8 and the depression 12 that is received in the referred to notch.

To the strip 6 as at 13, I propose to hinge- 80 edly secure a fastening element such as a pin 14 whereby the device per se may be readily secured to the blouse or dress.

A keeper 15 provided at one end of the strip 6 serves to retain the pin 14 in position, preventing displacement of the pin from the blouse or dress of the wearer. The blouse in this instance is indicated by the numeral 16.

In practice, I have found that by the use 90 of this simply constructed device a lingerie strap can be retained in a fixed position on the shoulder of the wearer so that the uncomfortable and unsightly slipping of the strap over the shoulder and onto the arms 95 of the wearer will be entirely eliminated.

It is to be understood that the form of my invention herewith shown and described is to be taken as a preferred example of the same and that various changes relative to the 100 size, material, shape and arrangement of parts may be resorted to without departing from the spirit of the invention or the scope of the subjoined claim.

Having thus described my invention, I 105 claim:

A device for retaining a lingerie strap comprising a top bar and a bottom bar, the bottom bar being pivotally secured at one end to said top bar and adapted to swing 110 horizontally with respect to said top bar, an upper and lower keeper element formed on

the opposite end of said top bar, a fastening element hingedly secured at one end to said top bar and adapted to swing vertically with respect to said top bar and detachably secured at its opposite end to the upper keeper element of the top bar, and locking means carried by said lower keeper element and

said lower bar for retaining therein the free end of said bottom bar so as to maintain said lower bar against accidental pivotal movement. 10

In testimony whereof I affix my signature.

INA PERMELIA JOHNSON.
